UNITED STATES PATENT OFFICE.

ROBERT J. GILMORE, OF PROVIDENCE, ASSIGNOR TO PRESTON L. BELDEN,
OF NORTH PROVIDENCE, RHODE ISLAND.

BUTTON.

SPECIFICATION forming part of Letters Patent No. 283,235, dated August 14, 1883.

Application filed June 6, 1883. (No model.)

To all whom it may concern:

Be it known that I, ROBERT J. GILMORE, a citizen of the United States, residing at Providence, in the county of Providence and State of Rhode Island, have invented certain new and useful Improvements in Buttons; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This my invention relates to certain improvements in buttons; and it consists, practically, of an eyelet having an enlarged flange, the latter being cut away to provide penetrating-prongs and a circular retaining base or flange which serves as the back of the button, the whole adapted to be attached to garments, &c., in any well-known manner.

In the accompanying drawings, made enlarged, Figure 1 represents a form of eyelet from which my improved button-back is made. Fig. 2 represents the same with a portion of its flange cut away, thereby leaving a circular flange and penetrating-prongs. Fig. 3 represents a vertical central section through the eyelet and prongs after the latter are bent and depending from the circular base. Fig. 4 represents a button in section complete and provided with my improvement, ready to be permanently attached to the garment or fabric. Figs. 5 and 6 represent common forms of buttons as provided with depending penetrating-prongs.

A in the drawings represents my improved button-back, made from a sheet-metal eyelet or

blank, A', Fig. 1, the latter being cut away to provide a series of penetrating-prongs, a², and 40 a circular base or table, a', which latter has a tubular shank, a, formed at right angles therewith, as shown.

The upper or outer end of the shank a is adapted to be secured to the front B of a button, said front being of any desired form. The opposite end of the tubular shank a terminates in the circular flange or base a', before referred to, from the periphery of which depends a series of prongs, a².

The advantage of the enlarged circular base a' consists, largely, in presenting a broad and smooth surface to the fabric, and at the same time avoiding the chafing or wear of the fabric incident to the use of the shouldered prongs, 55 as represented in Fig. 6.

The manner of attaching buttons to garments, &c., having my improvement is not essentially different from that usually employed for like purposes.

Having thus described my invention, what I claim as new, and desire to secure by Letters Patent, is—

As an improved article of manufacture, the piece A, constituting the shank and attaching portion of a garment-button, and consisting of the cylindrical shank a and base a', the latter provided at the outer edge thereof with attaching-prongs a², arranged and adapted for use substantially as shown and described.

In testimony whereof I have affixed my signature in presence of two witnesses.

ROBT. J. GILMORE.

Witnesses:

GEO. H. REMINGTON,
PRESTON L. BELDEN.
